SAFETY TREAD

Original Filed April 27, 1928

Inventor:
Howard G. Chapin,
by Right From Quincy, Mass.

Atlys.

UNITED STATES PATENT OFFICE

HOWARD G. CHAPIN, OF BOSTON, MASSACHUSETTS; G. EDWIN CHAPIN AND J. COLBY BASSETT, EXECUTORS OF SAID HOWARD G. CHAPIN, DECEASED, ASSIGNEES TO UNIVERSAL SAFETY TREAD INC., OF LOWELL, MASSACHUSETTS, A CORPORATION OF MASSACHUSETTS

SAFETY TREAD

Application filed April 27, 1928, Serial No. 273,360. Renewed January 2, 1930.

This invention relates to a safety attachment for a stair tread, composed of a base plate formed to bear on the upper surface of the stair tread, and a slab of rigid anti-slipping material secured to the base plate and presenting a horizontal upwardly facing frictional surface with which the shoe soles of pedestrians contact.

The chief object of the invention is to provide a safety tread, the antislipping surface of which is extended to project considerably forward from the front edge of the stair tread, and thus increase the area of said surface.

15 Of the accompanying drawings forming a part of this specification,—

Figure 1 is a perspective sectional view, showing a portion of my improved safety tread.

20 Figure 2 is a perspective sectional view, showing only the base plate and its channelled flange.

Figure 3 is a sectional elevation, showing the safety tread in its operative position on a 25 stair tread.

Figure 4 is a fragmentary view similar to a portion of Figure 3, showing the effect of wear.

The same reference characters indicate the 30 same parts in all of the figures.

In the drawings, 12 designates a flat base plate of sheet metal, formed to bear on the upper surface of a stair tread 13. Formed integral with the base plate is a substantially

35 U-shaped channel located at the forward portion of the plate. Said channel is composed of an inner wall 14, projecting downward from the plate 12, and formed to overlap and bear on the outer edge of the tread 13, a neck

40 15, projecting outward from the inner wall, and an outer wall 16, projecting upward from the neck and spaced from the inner wall, so that the channel has an open mouth. A slab of antislipping material, which may be any

45 50 of the compositions or mixtures usually employed in safety treads, is applied to the plate and channel while in a soft or plastic condition, and subsequently hardened. Said slab includes a body portion 17, which covers the plate, and a rib portion 17^c, which fills the

channel. The slab may be anchored in any suitable way, so that when hardened, it is firmly secured to the plate.

The exposed wear-sustaining surface of the layer includes an upwardly facing top face 17^a extended forward over the rib portion 17^c and a forwardly facing edge face 17^b extending downwardly from the forward portion of the top face to the outer wall 16 of the channel. The rib 17^c is backed and reinforced by the channel, and the face 17^b extends continuously from end to end of the safety tread, and constitutes an antislipping extension of the top face 17^a.

It will be seen that the projecting forward portion of the slab is thickened by the rib 17^c, so that it is adapted to sustain maximum wear on the edge face 17^b and on the forward portion of the top face 17^a, as indicated by full and dotted lines in Figure 4, the full line indicating the edge face after it has been worn away to a considerable extent. The wear thus indicated does not objectionably weaken the slab, and does not objectionably reduce the area of the antislipping surface, 75 because of the presence of the rib.

The faces 17^a and 17^b meet to form a salient wear-sustaining shoulder above the channel.

It will also be seen that the forward projection of the slab and channel from the outer edge of the stair tread, considerably increases the total area of antislipping surface presented by the tread, this increased area being an important advantage.

The safety tread to supplement the latter 85 may be attached by any suitable means to the stair tread.

I claim:

A safety tread adapted to supplement a stair tread, and comprising a metal base plate 90 formed to bear on the top of the stair tread and having a downwardly projecting channel adapted to project forward from the outer edge of said tread, said channel including a downwardly projecting inner wall, formed 95 to bear on said outer edge, an outwardly projecting neck, and an upwardly projecting outer wall spaced from the inner wall; and a slab of rigid antislipping material covering the base plate and including a downwardly 100

projecting rib filling the channel, an upwardly facing top face extended forward over the rib, and a forwardly facing edge face extending downward from the top face to the outer wall of the channel, said faces meeting to form a salient wear-sustaining shoulder, the forward portion of the slab being thickened by the rib and shoulder, and adapted to project forward from the forward edge of a stair tread to which the safety tread is applied, to extend the antislipping surface forward from the stair tread, the thickened projecting portion of the slab being supported by the channel portion of the base plate.

15 In testimony whereof I have affixed my signature.

HOWARD G. CHAPIN.
